US00D452554B1

(12) **United States Design Patent**
McKee et al.

(10) Patent No.: **US D452,554 S**
(45) Date of Patent: **** Dec. 25, 2001**

(54) **PUMP THERMAL PROTECTOR DEVICE**

5,105,988 * 4/1992 Knickerbocker 220/89.1
5,551,470 * 9/1996 Duvall 220/89.4

* cited by examiner

(75) Inventors: **Sheila McKee, St. Paul; Brian A. Kocher, Blaine, both of MN (US)**

Primary Examiner—Robin V. Taylor
(74) Attorney, Agent, or Firm—Oppenheimer Wolff & Donnelly; Steven C. Lieske

(73) Assignee: **GP Companies, Inc., Mendota Heights, MN (US)**

(57) **CLAIM**

(**) Term: **14 Years**

(21) Appl. No.: **29/131,899**

The ornamental design for a pump thermal protector device, substantially as shown and described.

(22) Filed: **Oct. 30, 2000**

DESCRIPTION

(51) LOC (7) Cl. **23-01**
(52) U.S. Cl. **D23/233; D9/448**
(58) Field of Search D23/233-236;
D9/448, 450, 300; 220/89.1, 89.4; 137/843,
853
